ADDISON G. WATERHOUSE, OF SAN FRANCISCO, CALIFORNIA.

Letters Patent No. 95,057, dated September 21, 1869.

IMPROVEMENT IN ROTARY MECHANICAL POWER.

The Schedule referred to in these Letters Patent and making part of the same.

To all whom it may concern:

Be it known that I, ADDISON G. WATERHOUSE, of San Francisco, in the county of San Francisco, and State of California, have invented a new and useful Improvement in Rotary Mechanical Power; and I do hereby declare that the following is a full, clear, and exact description thereof, reference being had to the accompanying drawings, and to the letters of reference marked thereon.

My invention relates to that class of mechanical gear in which a circulating cog-wheel propelled by a revolving eccentric or crank-shaft, operates within and upon a larger revolving cog-wheel, concentric with said driving-shaft, so as to rotate the said revolving cog-wheel by a slower motion than is imparted to the driving-shaft, but with a proportionate increase of power; and

My invention consists, first, in controlling the movement which is given to the circulating cog-wheel by the eccentric or crank, by means of a sliding ring or cross-arm, having an independent sliding bearing on opposite sides of the revolving shaft, and upon which ring or cross-arm the circulating wheel has a similar independent sliding bearing on opposite sides of the shaft, in a line at right angles to the sliding movement of said sliding ring or cross-arm; and

My invention further consists in making the inner portion of the circulating cog-wheel, which bears and slides directly upon the sliding ring or cross-arm, in the form of a detachable plate, which may be connected with or disconnected from said circulating cog-wheel, by means of an adjustable clutch, at pleasure, so that by disconnecting said plate, the circulating cog-wheel will cease to act upon the outer cog-wheel, and the latter will rotate with the same velocity as the revolving shaft.

My invention consists, further, in placing the revolving driving-shaft within a hollow stationary shaft, and in placing the sliding ways or bearings of the sliding ring or cross-arm upon the end of said stationary shaft, as hereinafter more particularly described.

My invention is applicable to ship-winches, capstans, windlasses, and all kinds of rotary machinery for concentrating power.

In the accompanying drawings—

Figure 1 is a central vertical section of a ship-winch, made pursuant to my invention, divided in line $x x$, fig. 3.

Figure 2 is a central vertical section of the same in line $y y$, fig. 3.

Figure 3 is an end view of the same, with the cover removed, to show the internal structure.

Figure 4 is a view of the circulating wheel moved by the eccentric.

Figure 5 is the sliding ring, which controls the movement of the circulating cog-wheel.

Figure 6 is a circulating plate, which, when in op-

eration, is secured to the circulating cog-wheel by a clutch, and becomes a portion thereof.

Figure 7 is an edge view of fig. 4.

Figure 8, an edge view of fig. 5.

Figure 9 is an edge view of fig. 6.

Figure 10 is a view of the inner face of disk H, on the end of the hollow stationary shaft.

Figures 11 and 12 are views of the rotating shaft and the eccentric or cap which operates the circulating wheel.

A is the body or drum of the winch;

A', a removable cover to the same;

B, the revolving driving-shaft;

B', the eccentric, mounted thereon;

C, the hollow stationary shaft, on which the drum revolves; and

D, the crank, by which the power is applied.

E is the outer revolving cog-wheel, which is made fast to the drum A, and revolves with it;

F is the circulating cog-wheel, moved by the eccentric B';

f is a circulating plate, forming a part of the circulating wheel F, when connected therewith by a clutch; and

g is the sliding ring, which controls the movement of the circulating wheel.

H is a circular disk, rigidly attached to the inner end of the hollow stationary shaft C.

On the face of the disk are two raised ways, h h, shown in fig. 10, extending radially on opposite sides of the revolving shaft.

The inner side of the sliding ring g has recesses g' on opposite sides, which fit down upon said ways h, so that said ring g can freely slide to and fro on said ways, which are stationary.

On the opposite side of said ring g, are two similar recesses, i i, at right angles with the recesses g', and on the inner face of the circulating plates f are two raised ways, j j, opposite each other, which fit into the recesses i i in the ring g, and allow the circulating plate f (and the circulating cog-wheel F, when attached thereto by the clutch,) to slide to and fro across the ring g, in a line at right angles with the sliding motion of said ring g upon the disk H.

As the ring g can only slide to and fro in one unvarying line across the stationary disk H, and the wheel F can only slide in one unvarying line at right angles thereto, across said ring g, the eccentric B', on the revolving shaft B, gives the wheel F a circulating, but not a rotary motion, so that its centre will move round a circle, but the wheel not revolve around its own axis; consequently, said wheel F, by its circulating motion within the larger wheel E, successively engages, on all sides, with the cogs of said wheel E, and at each revolution of the driving-shaft, moves the said wheel E to the extent of one cog.

In the drawing, the revolving wheel E has eight

cogs, and, consequently, it will require eight revolutions of the driving-shaft to rotate said wheel once.

It is manifest, however, that the gearing may be so modified as to increase or diminish the difference between the speed of the driving-shaft and the revolving wheel, by increasing or diminishing the throw of the eccentric or crank which actuates the circulating wheel.

The inner face of the circulating wheel F has projecting from it a series of studs or clutch-pins, k, which fit into a corresponding series of recesses k', in the circulating plate f.

The said wheel F is connected by three or more sliding rods, l, passing through the cover A', with a cap, L, outside of said cover. By pressing said cap L inward, the studs, or clutch-pins k, on the inner face of the circulating wheel F, are made to engage with the recesses k' in the circulating plate f, and so said plate becomes, practically, a part of the circulating cog-wheel, but, by drawing out the cap L, said circulating wheel F becomes disengaged from the plate f, and partially enters the cavity in the cover A', and there engages with a set of cogs, m, in said cover, which is rigidly fastened upon the rotating shaft, so that the revolving shaft and the drum will then revolve together at the same velocity.

On the outer side of the wheel F is a raised annular flange; l, forming under it an annular groove, into which hooks, on the inner ends of the rods l, enter, so as to clutch the said wheel for the purpose of moving it in and out, without preventing it from rotating.

Said annular flange l is eccentric to the revolving shaft, coinciding with the eccentric B', and the sliding rods l are set in a correspondingly eccentric circle in the cover.

In any machinery where it is desired to have a uniform rate of power, in proportion to the force applied to the driving-shaft, this clutching-device may be dispensed with, and the circulating plate f may be permanently attached to the circulating cog-wheel, or, in other words, may simply be a part thereof, and not a separate plate.

It is obvious that by applying the driving-power to

the outer revolving cog-wheel, the same gear may be used to accelerate motion, but in so using it I prefer a crank to actuate the circulating cog-wheel instead of the eccentric B'.

Instead of a ring, g, to actuate the circulating wheel, cross-arms may be substituted, in which case, two of the opposite radial arms will slide in suitable grooved ways, across the disk H, or other stationary bearing, while the other two arms will fit into recesses in the circulating cog-wheel F, or the circulating plate f, when one is interposed.

It will be seen that the sliding ring or cross-arm which controls the movement of the circulating wheel, has two independent sliding bearings on opposite sides of the revolving shaft, and does not rub against or come in contact with any part of the revolving mechanism.

Having thus fully described my invention, and its mode of operation,

What I claim as new, and desire to secure by Letters Patent, is—

1. In combination with the inner circulating cog-wheel, actuated by an eccentric or crank, as described, and the outer revolving cog-wheel, a sliding ring or cross-arm, having independent sliding bearings on opposite sides, and sliding bearings at right angles therewith, for the circulating wheel or plate, substantially as herein described.

2. In combination with the circulating cog-wheel, the circulating plate, with an adjustable clutch to attach and detach said plate to and from the circulating wheel, substantially as and for the purpose set forth.

3. In combination with the circulating and revolving cog-wheels and sliding ring or cross-arm, the revolving shaft B, the hollow stationary shaft C, and the stationary disk H, with sliding bearings thereon for the ring or cross-arm, substantially as described.

In witness whereof, I have hereunto subscribed my name, this 28th day of August, 1869.

ADDISON G. WATERHOUSE.
